(57) **CLAIM**

We claim the ornamental design for a computing device, substantially as shown and described.

DESCRIPTION

FIG. 1 is a front top perspective view of a computing device in accordance with the present design. The computing device may for example correspond to a personal computer. FIG. 2 is a rear bottom perspective view of the computing device.

FIG. 3 is a front view of the computing device.

FIG. 4 is a rear view for the computing device.

FIG. 5 is a right side view for the computing device.

FIG. 6 is a left side view for the computing device.

FIG. 7 is a top view for the computing device; and,

FIG. 8 is a bottom view for the computing device.
